UNITED STATES PATENT OFFICE

123,064

DESIGN FOR A CHIME SIGNAL HOUSING

Lloyd Rittenhouse, Honeoye Falls, N. Y., assignor
to The A. E. Rittenhouse Co., Inc., Honeoye
Falls, N. Y., a corporation of New York

Application August 30, 1940, Serial No. 94,745

Term of patent 7 years

To all whom it may concern:

Be it known that I, Lloyd Rittenhouse, a citizen of the United States of America and residing at Honeoye Falls, in the county of Monroe and State of New York, have invented a new, original, and ornamental Design for a Chime Signal Housing, of which the following is a specification, reference being had to the accompanying drawing, forming a part thereof.

In the drawing:

Fig. 1 is a front elevation of a chime signal housing showing my new design;
Fig. 2 is a side elevation of the same, and
Fig. 3 is a top plan view of the same.

I claim:

The ornamental design for a chime signal housing, as shown.

LLOYD RITTENHOUSE.
